UNITED STATES PATENT OFFICE.

FRANZ TRINKS, OF BRUNSWICK, GERMANY.

CALCULATING-MACHINE.

1,149,872.

Specification of Letters Patent. Patented Aug. 10, 1915.

Application filed November 27, 1914. Serial No. 874,325.

To all whom it may concern:

Be it known that I, FRANZ TRINKS, manufacturer, a citizen of the Duchy of Brunswick, Empire of Germany, residing at 5 Brunswick, Germany, have invented certain new and useful Improvements in Calculating-Machines, of which the following is a specification.

My invention relates to improvements in calculating machines, and more particularly in calculating machines which are provided with setting disks on which the values are set by setting the corresponding number of teeth into operative positions, one setting 10 disk corresponding to each order, the first one from the right corresponding to the units, the second one to the tenths, the third one to the hundredths, etc.

More particularly my invention relates to 20 means for setting the said teeth in inoperative or rocked positions and in operative positions.

The object of the improvements is to provide a machine of this class in which the 25 teeth provided on the setting disks are adapted to be set in operative and inoperative positions by means of levers which have rocking supports on the shaft carrying the setting disks.

For the purpose of explaining the invention several examples embodying the same have been shown in the accompanying drawings, in which the same letters of reference 30 have been used in all the views to indicate corresponding parts.

In said drawings—Figure 1, is a cross-section of the machine, Fig. 2, is a front view of one of the setting disks and the parts connected therewith, Fig. 3, is a cross-40 section similar to that shown in Fig. 1 and showing a modification, Fig. 4, is a front view of Fig. 3 similar to that shown in Fig. 2, Fig. 5, is a detail view, Fig. 6, is a front view similar to that shown in Fig. 2 and 45 showing a further modification of the mechanism, and Fig. 7, is a side view showing a detail of the mechanism illustrated in Fig. 6.

The general construction of the machine 50 to which my invention more particularly relates will be best understood from Figs. 1 and 2. As shown in the side walls of the machine a shaft *b* is mounted which is adapted to be rotated by means of a machine crank *z*, and which carries several setting disks *a* provided with teeth *d*. The

said teeth are adapted to be brought into positions for engagement with intermediate gear wheels *e* corresponding one to each of the setting disks and coöperating with gear wheels *w* connected with numeral wheels *w'* the figures of which are displayed through peep holes *v* made in the cover of the casing of the machine. Ordinarily the teeth *d* are in their inoperative positions in which they 60 do not impart rotary movement to the intermediate gear wheels and the numeral wheels, when the shaft *b* is rotated by the machine crank. In order to transmit a certain value to the numeral wheels, the corresponding number of teeth *d* is first set in 65 operative position, whereupon the machine crank is rotated. Thereby the value set on the setting disks is transmitted to the numeral wheels and displayed through the 70 peep holes. By twice rotating the crank 75 the double number is displayed through the peep holes etc.

In combination with the parts briefly referred to carrying and resetting mechanisms 80 are provided. As such means are familiar to those skilled in the art and my invention does not particularly relate to such means I have not illustrated the same in the drawings.

In order that the teeth *d* can be set in operative positions, they are rockingly mounted at points intermediate their ends on small axes *d'* which are located in the plane of the disks *a*, as is shown in Fig. 2. 90 When a tooth has been rocked to the side it revolves with the disk *a* without engaging the intermediate gear wheel *e*, and when it is rocked from the inoperative position into the position in which it is parallel to the 95 plane of the setting disk *d*, it engages in the teeth of the coöperating intermediate gear wheel upon rotation of the disk by the machine crank.

My invention relates more particularly to 100 the mechanism for setting the teeth *d* in the rocked or inoperative and in the operative positions.

At the side of each of the disks *a* a lever *c* is loosely mounted on the shaft *b*, and the 105 said lever is formed at its end with a hand piece *c'* projecting through a slit *f* made in the cover of the casing *f*. The lever *c* is formed with two noses *i* and *k* having cam faces, and the distances of the said noses 110 from the shaft *b* correspond to the distances of the ends of the teeth *d* from the shaft.

The noses *i* and *k* are staggered in relation to each other in circumferential direction, as is shown in Fig. 1. The dimensions of the noses *i* and *k* and the teeth *d* are such, that when rocking the levers *c* in the direction of the arrow *x* shown in Fig. 1, at first the nose *k* strikes along a lateral projection *d*⁴ formed on the lower part of the tooth *d*, and that thereafter the nose *i* engages the upper end of the tooth *d* and rocks the same in operative position. When rocking the lever *c* backward and in the direction of the arrow *y* shown in Fig. 1, at first the nose *i* moves along the upper end of the tooth *d* without acting on the same, and thereafter the lower nose *k* strikes the projection *d*⁴ made at the lower end of the tooth *d* and rocks the same into inoperative position. The levers *c* and the disks *a* are adapted to be locked relatively to each other in either one of the ten positions in which they can be set by a yielding locking mechanism, which as shown consists of a toothed sector *g* connected or made integral one with each of the levers *c* and a spring actuated latch *h* secured one to each of the disks *a*. If desired the said sectors can be connected with the disks and the latches with the levers *c*.

For locking the teeth *d* in their positions the following mechanisms are provided: Each of the teeth carries at its lower end a nose *d*² and on each of the disks *a* a spring actuated latch pin *t* is mounted which is similar in construction to the pins *h*. In one of their positions the noses *d*² are located at the right and in the other one at the left of the pins *t*.

According to my invention the mechanism is constructed in such a way, that by means of the levers *c* the teeth *d* are rocked only from one position into the other one, and that for locking the teeth in either position the parts *d*² and *i* are used which are entirely independent of the levers *c*.

In Figs. 3 and 4 I have shown a modification of the invention in which the levers *c*² and their hand pieces *c*³ which in the example shown in Figs. 1 and 2 take part in the rotation of the disks *a* are stationary relatively to the disks, so that they can have any desired length and thickness. For this purpose the setting levers *c*² are pivotally mounted on their hubs *m* so that they can be rocked about the axis *o* in the direction toward the shaft. Springs *p* have the tendency to pull the levers away from the disks *a*, so that their noses *i*¹ and *k*¹ are out of positions for engagement with the teeth *d* or lateral projections formed thereon when the disks are being rotated. But if it is desired to set a value on the setting disks, the levers *c*² are rocked by means of the hand pieces *c*³ to the right, whereupon setting can be performed. The means for locking the levers *c*² in either positions are constructed

in such a way, that the spring actuated latch pins *h*¹ are not mounted on the disks *a* but on the machine frame.

In order that the levers *c*² be rocked sufficiently to the right prior to setting a value or returned into inoperative positions after the values have been set on the setting disks, so that they are in positions for engagement with the teeth *d* or the lateral noses thereof, the slits *f*¹ made in the cover of the casing *f* and permitting the passage of the hand pieces *c*³ therethrough can be made in the manner shown in Fig. 5, in which indentations are shown at the left hand side walls of the slits. Thereby the operator must rock the hand piece *c*³ the proper distance to the right before setting can take place.

In the modification of the construction shown in Fig. 6 rods *s* are provided in lieu of the levers *c* or *c*², which rods are shiftable within sleeves *v* radially of the shaft *b* and in opposition to springs *t*. The sleeves have rocking supports on the shaft *b*, and the rods *s* carry lateral noses *i*³ and *k*³, and by depressing the rods the said noses are brought into positions for engagement with the ends or lateral projections of the teeth *d*. Also in this case means may be provided for forcing the operator to depress the rods *s* sufficiently prior to rocking the sleeves *v*. To show what may be done toothed sectors *i*² are provided on the lower side of the casting *f*, and the indentations of the said sectors are in such positions, that they are engaged by the noses *i*³ or special noses or stop members formed on the rods *s* when in the uppermost positions. In this case setting is not possible before the head of the rods *s* have been depressed.

I claim herein as my invention:

1. In a calculating machine, the combination with the registering mechanism, and the setting disks coöperating therewith and having rocking teeth arranged about their circumferences, of members one for each of the setting disks adapted to be moved along said teeth and arranged for engagement respectively with the ends of the teeth and at opposite sides of the fulcrums thereof and when moved along the teeth for rocking the same, and independent means to hold the teeth in operative and inoperative positions.

2. In a calculating machine, the combination with the registering mechanism, and the setting disks coöperating therewith and having rocking teeth arranged about their circumferences, of members one for each of the setting disks adapted to be moved along said teeth and arranged for engagement respectively with the ends of the teeth and at opposite sides of the fulcrums thereof and when moved along the teeth for rocking the same, means for locking the members relatively to the disks in their positions relatively to the teeth, and independent means

to hold the teeth in operative and inoperative positions.

3. In a calculating machine, the combination with the registering mechanism, and the setting disks coöperating therewith and having rocking teeth arranged about their circumferences, of members one for each of the setting disks adapted to be moved along said teeth and arranged for engagement respectively with the ends of the teeth and at opposite sides of the fulcrums thereof and when moved along the teeth for rocking the same, said movable members being so mounted, that they can be moved with the parts engaging the teeth out of the paths of the teeth, locking means for holding the movable members in their positions in and out of the paths of the teeth, and independent means to hold the teeth in operative and inoperative positions.

4. In a calculating machine, the combination with the registering mechanism, a rotary shaft, setting disks mounted on said shaft and coöperating with the registering mechanism, and rocking teeth arranged about the circumferences of the disks, of members on said rotary shaft one for each of the setting disks adapted to be moved along said teeth and having parts which are rockingly mounted on pins substantially parallel to the planes of the disks and are adapted to engage the teeth respectively at opposite sides of the fulcrums thereof and when moved along the teeth to rock the same, locking means for holding the movable members in and out of the paths of the teeth, and independent means to hold the teeth in operative and inoperative positions.

5. In a calculating machine, the combination with the registering mechanism, a rotary shaft, setting disks mounted on said shaft and coöperating with the registering mechanism and having rocking teeth arranged about their circumferences, and a casing enclosing said registering mechanism, of members on said shaft one for each of the setting disks adapted to be moved along said teeth and having parts which are rockingly mounted on pins substantially parallel to the plane of the disks and are adapted to

engage respectively with the ends of the teeth at opposite sides of the fulcrums thereof and to rock the teeth, said members projecting through slits made in the wall of the casing and adapted to engage in indentations made in the side walls of said slits, and independent means to hold the teeth in operative and inoperative positions.

6. In a calculating machine, the combination with the registering mechanism, and the setting disks coöperating therewith and having rocking teeth arranged about their circumferences, members one for each of the setting disks movable along said teeth and having longitudinally shiftable parts which are adapted when moved along the teeth to engage respectively with the ends of the same at opposite sides of the fulcrums thereof and to rock the same, said shiftable parts being so mounted that they can be shifted out of coöperation with the teeth, springs tending to hold the members in inoperative positions, and independent means to hold the teeth in operative and inoperative positions.

7. In a calculating machine, the combination with the registering mechanism, and the setting disks coöperating therewith and having rocking teeth arranged about their circumferences, of members one for each of the setting disks movable along said teeth and having longitudinally shiftable parts which are adapted when moved along the teeth to engage respectively with the ends of the teeth at opposite sides of the fulcrums thereof and to rock the same, said shiftable members being so mounted that they can be shifted out of the paths of the teeth, relatively fixed toothed sectors adapted to be engaged by the shiftable parts when out of operative positions, and independent means to hold the teeth in operative and inoperative positions.

In testimony whereof I have hereunto set my hand in presence of two subscribing witnesses.
